Primary Examiner — Darlington Ly(57) **CLAIM**

The ornamental design for a tricycle frame, as shown and described.

DESCRIPTION

1. Tricycle frame

1.1 is a top, front, and right side perspective view of a tricycle embodying my new design;

1.2 is a top, rear, and left side perspective view thereof;

1.3 is a top, front, and right side perspective view of the tricycle frame portion shown in 1.1 and 1.2;

1.4 is a top, rear, and left side perspective view thereof;

1.5 is a top plan view thereof;

1.6 is a bottom plan view thereof;

1.7 is a right side elevation view thereof;

1.8 is a left side elevation view thereof;

1.9 is a front elevation view thereof; and

1.10 is a rear elevation view thereof.
